UNITED STATES PATENT OFFICE

96,021

DESIGN FOR A CLOCK OR SIMILAR ARTICLE

Ostilio Ciccarelli, Bristol, Conn., assignor to The
E. Ingraham Company, Bristol, Conn., a cor-
poration

Application April 19, 1935, Serial No. 56,467

Term of patent 14 years

To all whom it may concern:

Be it known that I, Ostilio Ciccarelli, a citizen of the United States, residing at Bristol, in the county of Hartford and State of Connecticut, have invented a new, original, and ornamental Design for a Clock or Similar Article, of which the following is a specification, reference being had to the accompanying drawing, forming part thereof.

Fig. 1 is a perspective view of a clock or similar article showing my new design; and

Fig. 2 is a view thereof in front elevation.

The dominant characteristics of applicant's design reside in a tambour type of clock in which the height is approximately one-third or less of the length, and in which a substantial portion of the front, central, bottom edge depends downwardly below the adjacent flanking portions of the front bottom edge.

I claim:

The ornamental design for a clock or similar article substantially as shown and described.

OSTILIO CICCARELLI.
